CLAIM

The ornamental design for a magnetic clip, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a top view of a magnetic clip showing my new design;

FIG. 2 is a bottom view of FIG. 1;

FIG. 3 is a top, left side perspective view of FIG. 1;

FIG. 4 is a bottom, right side perspective view of FIG. 1;

FIG. 5 is a left side view of FIG. 1;

FIG. 6 is a right side view of FIG. 1;

FIG. 7 is a perspective view of FIG. 1, shown in a used condition in a secured position;

FIG. 8 is an opposite side perspective view of FIG. 7;

FIG. 9 is a top view of FIG. 7;

FIG. 10 is a side view of FIG. 7; and,

FIG. 11 is an opposite side view of FIG. 9.

The broken lines form no part of the claimed design.
